**MULTI-PHASE SWITCH ARRANGEMENT
MOUNTED ON A SINGLE POLE**

Lawrence G. Pilgrim, Youngwood, and Donald J. Hamrock, Greensburg, Pa., assignors to I-T-E Circuit Breaker Company, Philadelphia, Pa., a corporation of Pennsylvania

Filed Jan. 24, 1963, Ser. No. 253,568
4 Claims. (Cl. 200—48)

This invention relates to electrical transmission and distribution systems and more particularly to a novel switching arrangement for such systems which employs a mounting for each phase of a multiphase system which cooperates in such a manner with the other mountings of the multiphase system to provide a mounting assembly which is rugged, reliable and which occupies far less space than switching arrangement of the prior-art.

In outdoor electrical equipment employed in the transmission and distribution of electrical power, switching arrangements for such systems find widespread use for the interruption of transformer magnetizing current, line charging current, or loop currents, for picking up and interrupting line charging current when switching from one feeder line to another, or for changing the feeder connection from a preferred source to an emergency source. In the performance of the above functions it is necessary to provide a switching arrangement which in addition to having the above capabilities must be adaptable for use in applications where extra real estate is unavailable or where real estate is extremely costly.

One switching arrangement which is presently in use is comprised of three wood pole structures wherein a first structure is provided for receiving the incoming source wires and tying the source wires of each phase to suitable strain insulators. A second structure is employed for mounting a plurality of switches associated with each phase wherein the first terminal of each switch is connected to the incoming source wires and the second terminal of each switch is connected to suitable feeder lines. A third structure is provided which has mounted thereupon suitable switches for connecting the source lines to a like number of feeder lines in the same manner as the switches mounted on the second structure. This arrangement is quite costly in both the amount of real estate involved and in the amount of equipment necessary to make up the completed two-way switching arrangement.

The instant invention provides a two-way switching arrangement for receiving source lines and connecting them to either one or both feeder lines connected thereto while enabling the entire switching arrangement to be mounted upon a single wood pole. In addition thereto, the switching assembly for each phase of the multiphase system is mounted upon the pole in a manner which facilitates guying the wood pole to resist forces created by line strain pulls.

The instant invention is comprised of a single mounting pole having a plurality of switch assemblies positioned in vertical alignment along the length of the pole. The number of switch assemblies employed in the vertical array depends only upon the number of phases in the electrical distribution system, usually a 3-phase system.

The switch assembly for each phase is comprised of a substantially triangular shaped base member mounted

2

vertically, having first and second switch devices mounted thereto so that the plane of motion of the blade member of each switch assembly is also in the vertical plane. A suitable strain insulator is mounted upon and centrally located within the switch assembly base member so that it projects in a horizontal direction. The incoming line is coupled from the strain insulator to a terminal which is common to one end of said first and second switch assemblies. This common terminal is mounted upon a suitable insulator to electrically insulate it from the base member of the switch assembly. The opposite ends of the switch assemblies are mounted to the base assembly in a like manner by means of second and third insulator members. Both the strain insulator and the switch mounting insulators are all oriented in the horizontal plane. Each of the base members of the switch assemblies are mounted so that they lie in a vertical plane which results in a substantial reduction in the cantilever forces exerted upon the wood pole. This permits easier installation of guy wires to resist the line strain pulls.

It is therefore one object of this invention to provide a switching arrangement for outdoor electrical distribution and transmission systems which is so adapted as to permit the mounting of the switch assembly for all phases upon a single wood pole.

Another object of this invention is to provide a novel switching arrangement for outdoor electrical systems having a novel switch assembly base member for each phase of the switching system which is oriented to the mounting wood pole so as to substantially reduce cantilever forces exerted upon the pole.

Another object of this invention is to provide a switching arrangement for multiphase outdoor electrical systems wherein the strain insulator for the switch assembly of each phase is mounted in a central location with respect to the switch assembly base member which decreases the necessary phase spacing required for the over-all switch assembly.

Still another object of the instant invention is to provide a switching arrangement having a novel design which employs normal gravitational forces in such a manner that gravity holds the switching assembly blade means in their intended positions.

These and other objects will become apparent when reading the accompanying description and drawings in which:

FIGURE 1a shows a top plan view of a prior art two-way switching arrangement.

FIGURE 1b is an elevational view of the two-way switching arrangement of FIGURE 1a.

FIGURE 2a is an elevational view of the two-way switching arrangement of the instant invention.

FIGURE 2b is a side view of FIGURE 2a looking in the direction of arrows 2b—2b'.

FIGURE 3 shows an elevational view of a portion of FIGURE 2a in greater detail.

Referring now to the drawings; FIGURES 1a and 1b shows a prior art two-way switching arrangement 100 which is comprised of incoming source lines 101a—101c wherein each line is provided for one-phase of a three-phase system, for example. The source lines 101a—101c may be connected to any suitable source such as the secondary windings of a step-up transformer, a step-down transformer, and so forth, employed in the electrical sys-

tem. As another example, lines 101a-101c may be connected to the three phases of a load and thereby act as feeder lines, in a manner to be more fully described. The incoming lines 101a-101c terminate in strain insulators 102a-102c at structure 103 which is provided for dead-ending the lines and which is also necessary for this arrangement. Strain insulators 102a-102c are mounted on a suitable structure 103, which is mounted to a wood pole member 104. Lines 101a-101c are tapped at points 115a-115c, respectively, so as to be connected to lines 105a-105c. The left-hand end of lines 105a-105c are connected to the right-hand terminals of switches 106a-106c which are mounted upon a suitable platform 107 positioned atop wood mounting pole 110. Each switch 106a-106c is capable of assuming either a fully closed or fully open position so as to electrically connect or disconnect, respectively, lines 105a-105c to lines 109a-109c, respectively. Lines 109a-109c may be feeder lines connected to any suitable load means or as previously mentioned, may be connected to the three-phase leads of a suitable source which may be employed to feed electrical energy to lines 101a-101c, which in this situation would be acting as feeder lines.

The switches 113a-113c mounted upon wood pole 111 are electrically connected with lines 105a-105c and 114a-114c, respectively, in the same manner as are switches 106a-106c and switches 113a-113c operate in a like manner.

The operation of the switching arrangement 100 may be such that, assuming lines 101a-101c are connected to the three-phase lines of a suitable energy source with the switches 106a-106c and 113a-113c being in their closed position, energy will be fed to the load means (not shown) connected to the feeder lines 109a-109c, respectively, and 114a-114c, respectively. Thus, the single source may be employed to feed two independent loads. As a second arrangement, the switch assemblies 106a-106c and 113a-113c may operate in an alternative fashion such that when lines 109 and 114 are feeder lines, one bank of switches, such as, for example, the bank 106a-106c may be opened in order to interrupt line charging current and in the reverse when switching back, switches 106a-106c are closed to pick up line charging current and feeder switches 113a-113c are then opened to interrupt charging current. Lines 109a-109c and 114a-114c may be connected to suitable energy sources which are employed to supply one feeder line wherein lines 101a-101c act as the feeder lines. With such an arrangement switches 113a-113c would be in an open state while switches 106a-106c are in the closed position so that the feeder lines 101a-101c are connected to the source lines 109a-109c, respectively. In switching from one source to another, switches 106a-106c may first be open so that switches 113a-113c may be closed in order to connect the source lines 114a-114c to the feeder lines 101a-101c, respectively.

As can be seen, the above arrangement requires at least three wood poles and a large amount of supporting structures for the switch assemblies and strain insulators and further requires a substantial amount of real estate upon which to construct the two-way switching arrangement.

FIGURES 2a and 2b and 3 show the switching arrangement 200 designed in accordance with the principles of the instant invention, which arrangement 200 is comprised of a single wood pole 250 upon which are mounted the two-way switching assemblies 201a-201c wherein each switching assembly 201 is provided for connection to one phase of a three-phase system. While the embodiment of FIGURES 2a and 2b shows an arrangement for a three-phase system, it should be understood that the instant invention operates equally as well for greater or lesser phases and the embodiment described herein should be considered as merely exemplary. As each of the two-way switching assemblies 201a-201c are substantially identical to one another, only one of these switching assemblies, namely, 201a, will be described in detail, it being understood that

the design and operation of the others are substantially the same.

The switching assembly 201a is comprised of a triangular shaped base member 202a which is suitably secured to a vertically aligned member 203a which in turn is fastened to pole 250 at its upper and lower ends by fastening members 204a and 205a, respectively. It can be seen from FIGURES 2a and 2b that the base member 202a is oriented so that the plane of base member 202a is vertically oriented. A fastening flange 275a is secured to and intermediate the ends of vertically aligned member 203a and is provided for the purpose of mounting a strain insulator 206a thereto. The incoming conductor 220a for phase A of the three-phase system is connected to a Y-shaped strain clamp member 221a which has one arm terminating in an eyelet 276a in strain insulator 206a. The other arm of Y-shaped member 221a is connected by means of conductor 222a to a terminal 224a which is electrically connected to a first end of both switching assemblies 210a and 201a for a purpose to be more fully described.

Base member 202a has insulators 207a, 208a and 209a, each being positioned at the vertices of the triangular base member. A switch assembly 210a is mounted upon the insulators 207a and 209a and a second switch assembly 201a is mounted upon the insulators 208a and 209a. The switch assembly 210a is comprised of a movable blade assembly 212a which pivots about a point 278a which is concentric with insulator member 207a. Blade 212a is shown in the fully closed position and upon operation thereof for interrupting current purposes blade 212a moves in the direction shown by arrow 279a towards the position occupied by the blade assembly 212a' of the switch assembly 201a. During the closing operation the reverse is true. Namely, the blade assembly, such as the blade assembly 212a', which is in the open position, is moved in the direction shown by arrow 281a in order to close interrupter switch 201a. It should be understood that both the switch assemblies 210a and 201a operate substantially in the identical manner. Blade assembly 212a cooperates with a jaw assembly 213a which pivots about a pivot point 282a. The blade assembly 210a is provided with an actuating lever arm 211a which is moved by the actuating means which will subsequently be described in greater detail so as to move blade assembly out of engagement with the jaw assembly 213a. Since the blade assemblies 210a and 201a lend no novelty to the instant invention, it will not be described in great detail. However, these side opening disconnect switches may be of the type set forth in U.S. Patent 2,688,667 entitled Side Opening Shuntless Disconnect Switch, issued September 7, 1954 to A. Foti and assigned to the assignee of the instant invention. The description set forth in this U.S. patent is hereby incorporated herein by reference. The terminal pad 271a is electrically connected to the hinged end of blade assembly 212a and is utilized for connecting the incoming conductor thereto. The hinged end 282a of movable jaw 213a is electrically connected to terminal 224a which is provided with a suitable terminal pad 287a for connecting an electrical conductor thereto. As can clearly be seen in FIGURE 2a the rotatable end 282a of pivoting jaw assembly 213a is likewise electrically connected to electrical terminal 224a thereby forming a junction between the incoming conductor (not shown) connected to the terminal pad 287a and the rotatable ends 282a of the switch assemblies 210a and 201a. The rotatable end 278a' of blade assembly 212a' is likewise provided with a terminal pad 271a' for connecting a conductor thereto. With the switch assemblies 210a and 201a in the positions as shown in FIGURE 3, it can clearly be seen that an electrical path is established between the terminal pad 287a which receives an incoming conductor through to the terminal pad 271a which is likewise suitable for receiving an incoming conductor. In addition thereto with switch assembly 201a

being in the open position no electrical connection is established between terminal pad 287a and 271a'.

The interrupter switches 210a, 210b and 210c of the switch assemblies 201a, 201b and 201c of the three-phase distribution network are all moved to their open and closed positions simultaneously by the ganged operating structure 240. The interrupter switch operating structure 240 is comprised of an operating handle 242 having a hand-grip 242a at a first end thereof and is pivotally connected to a support member 241 at pivot point 244 so as to be movable in an arc which lies in a vertically aligned plane. Support member 241 is secured to the mounting wood pole 250 by fastening members 243. Operating arm 242 is pivotally connected at pivot point 291 to a substantially L-shaped member 245 which is suitably secured to the lower end of a rod 246. It should be noted that the interrupter switches 210a-210c of the switch assemblies 201a-201c are ganged for simultaneous operation with the manual operating structure 240' which is substantially identical to the operating structure 240. However, from examination of FIGURE 2a, it can be seen that the operating structure 240 is in the position whereby the interrupters such as 210a-210c are in their closed position while the position of operating structure 240' has moved interrupter switches 201a-201c to the fully opened position. Thus, L-shaped member 245' is substantially identical to the member 245 of operating assembly 240.

The upper end of rod 246 terminates in an arm 247 which pivotally connects rod 246 to a movable link 249 at a pivot point 248. One end of link 249 is pivotally connected at point 251 to a support member 252 which is secured to pole 250 by fastening members 252a. The opposite end of link 249 is pivotally connected at point 253a to member 253 which is suitably connected to lower end of rod 254. The upper end of rod 254 terminates in a member 255 which is pivotally connected at point 257a to an arm 256a which is employed for the purpose of actuating the operating lever 211a of switch assembly 210a, in a manner to be more fully described. This actuating arm 256a is secured to a shaft 272, which is rotatably mounted in base member 202a and which is provided with a second actuating arm 293a which is likewise secured to shaft 272a. The free end of arm 293a is pivotally connected at point 294a to a rod 259a which terminates in a member 260a which is pivotally connected to the free end of interrupter switch operating arm 211a at pivot point 294a.

The opening operation for interrupter switch 210a and simultaneously therewith for the interrupting switches 210b and 210c is as follows:

Manual operating handle 242 is rotated counterclockwise about its pivot point 244 in the direction shown by arrow 295 causing L-shaped member 245 to move substantially vertically upward thereby urging members 246 and 247 in the upward direction. This causes movable link 249 to rotate clockwise in the direction shown by arrow 296 thereby urging member 253 to move substantially vertically upward. As can be noted, member 253 is connected further out on movable link 249 than member 247 thereby causing member 253 to move vertically upward an amount which is proportional to the distances of the pivot points 253a and 248 from the pivot point 251. This upward movement of member 253 is imparted to rod 254 and member 255 causing actuating lever 256 to rotate counterclockwise in the direction shown by arrow 297. Since lever arm 256a is rigidly secured to shaft 272a this causes shaft 272a to likewise rotate in the counterclockwise direction. This rotation is also imparted to lever arm 293a which movement is imparted to rod 259a causing it to move substantially in the linear direction shown by arrow 301. This movement is imparted to member 260a which causes operating arm 211a of the interrupter switch 210a to move blade assembly 212a of the disconnect switch 210a in the direction shown by arrow 279a

thus causing the interrupter switch assembly to move to the fully open state such as is occupied by the disconnect switches 201a-201c shown in FIGURE 2a.

Disconnect switches 210b and 210c are provided with similar connecting linkages and simultaneously move to the open position together with the opening of disconnect switch 210a in a manner substantially identical to that described above. The opening forces are imparted to disconnect switches 210b and 210c by rods 261 and 262 which are linked together in series with rod 254 so that any vertical upward movement of rod 254 is directly imparted to rods 261 and 262.

The closing operation is performed by moving operating handle 242 from the downward position (such as is shown by the handle 242') and rotating handle 242 clockwise in the direction shown by arrow 302. This causes L-shaped member 245 and rods 246, 254, 261 and 262 to move vertically downward. This reverses the movement of the connecting linkages ultimately causing the blade assemblies 212a-212c to move from their open position (which would be the mirror image of the disconnect switches 201a-201c) clockwise about their pivot points 278a as shown by arrows 304a-304c so that they return to their fully closed position, as is already shown in FIGURE 2a.

Disconnect switch operating assembly 240' is mounted on the opposite side of wood pole 250 and operates in a manner substantially identical to the operation of assembly 240 so as to move disconnect switches 201a-201c between their opened and closed positions. Each of the disconnect switch operating assemblies 240 and 240' are provided with jumper cables 270 shown in FIGURE 2b in order to suitably place all of the operating elements at ground potential.

Each of the supporting members 241 and 241' are provided with suitable openings 305 and 305' which cooperate with openings (not shown) provided in handle members 242 and 242', respectively, for the receipt of padlock means so as to enable locking of the handle assemblies in either the open or closed positions of the disconnect switches associated with each operating assembly. It should be understood that two separate openings are provided in the handle assembly 242 so as to cooperate with the opening 305 when the disconnect switches are in the fully closed position as shown by the disconnect switches 210 and provided with the second opening (not shown) to cooperate with the opening 305' for padlocking purposes when the disconnect switches are in the open position, as shown by switches 201a-201c.

As can best be seen in FIGURE 2b, the base members 202a-202c of each switch assembly 201a-201c are positioned relatively close to and in vertical alignment with the mounting pole 250 thereby substantially reducing the cantilever forces imposed upon the mounting pole 250. This permits the use of substantially lighter weight guy wires which may be needed in order to provide added supporting strength for the two-way switching arrangement 200. Due to the horizontal orientation of the insulator members 207-209, as well as the strain insulators 206, the clearance required between adjacent phases, namely, the clearance required between phase A and B and between phase C and D is substantially decreased thereby permitting usage of a substantially shorter pole than would be the case if the base members 202a-202c were oriented so that their planes were parallel to the horizontal direction. The diminished clearances of the switch assemblies of each phase and the necessarily shorter pole resulting therefrom further aid in the diminishing of cantilever forces imposed upon the pole and also substantially reduce the cost of the over-all structure. The vertical alignment of the base members 202a-202c also permits an extremely favorable mounting location for the strain insulators 206a-206c. Thus the strain of the source lines is resisted almost entirely by the mounting pole 250 rather than by

the base members 202a-202c. This permits use of a lighter weight base thereby diminishing the total weight imposed upon the mounting pole 250. In addition thereto, with the disconnect switches mounted in the manner as shown in FIGURES 2a and 2b the resistive forces acting against the operating handles 242 and 242' of the operating assemblies 240 and 240', respectively, are significantly reduced thereby reducing the manual exertion necessary to open or close the disconnect switches 210 and 210'.

An important feature of this switch arrangement is that gravity holds the switch blades in the intended position. Switch 210 of FIGURE 2a is held closed by the weight of its own blades, as 201 is held open by the weight of its blades.

Although there has been described in a preferred embodiment of this novel invention, many variations and modifications will now be apparent to those skilled in the art. Therefore, this invention is to be limited, not by the specific disclosure herein, but only by the appending claims.

The embodiments of the invention in which an exclusive privilege or property is claimed are defined as follows:

1. A switching arrangement for use in multiphase outdoor electrical distribution systems comprising a mounting pole; a plurality of switching assemblies equal in number to the number of phases of said multiphase system mounted upon said mounting pole; each of said switching assemblies comprising a substantially flat base member and four insulator members positioned perpendicular to said base member, the plane of said base member being substantially parallel to the central axis of said pole; first and second disconnect switches insulatingly mounted to said base member, each of said switches having a rotatable side opening switch blade means; the rotational motion of said blade means lying in a plane parallel to the plane of said base member each of said blade means being movable to an open and a closed position, wherein normal gravitational forces aids in retaining the blade means in either position to which the blade means is moved.

2. A switching arrangement for use in multiphase outdoor electrical distribution systems comprising a mounting pole; a plurality of switching assemblies equal in number to the number of phases of said multiphase system mounted upon said mounting pole; each of said switching assemblies comprising a substantially flat base member, the plane of said base member being substantially parallel to the central axis of said pole; first and second disconnect switches insulatingly mounted to said base member; an insulator member having a first end secured to said mounting pole substantially at the center of said base member; said insulator member being positioned substantially perpendicular to the plane of said base member to receive an incoming electrical conductor at its second end, second, third and fourth insulator members secured to said base member for insulatingly mounting said disconnect switches to said base member; said second, third and fourth insulators being substantially parallel to said first insulator, the switch assemblies being vertically aligned along said mounting pole; manually operable means movably mounted to said mounting pole for moving said disconnect switches between their open and closed positions; said manually operable means including a linkage system for ganging the disconnect switches of all phases to said manually operable means causing said disconnect switches to become simultaneously operative under control of said manually operable means; each of said switches having a rotatable side opening switch blade means; the rotational motion of said blade means lying in a plane parallel to the plane of said base member; each of said blade means being movable to an open and a closed position, wherein normal gravitational forces aids in retaining the blade means in either position to which the blade means is moved.

3. A switching arrangement for use in multiphase outdoor electrical distribution systems comprising a mounting pole; a plurality of switching assemblies equal in number to the number of phases of said multiphase system mounted upon said mounting pole; each of said switching assemblies comprising a substantially flat base member, the plane of said base member being substantially parallel to the central axis of said pole; first and second disconnect switches insulatingly mounted to said base member, said base member comprising a triangular shaped frame; first, second and third insulator members having their first ends secured to said frame at the corners thereof; fourth insulator means having its first end secured to said mounting pole at substantially the center of said frame; said first, second, third and fourth insulators being substantially parallel to one another, the second end of said fourth insulator being adapted to receive an incoming electric cable; each of said disconnect switches having a first and a second end, the first ends being secured to the second ends of said second insulator; the second ends of each of said disconnect switches being secured to the second ends of said third and fourth insulators, respectively, said first end of each disconnect switch being electrically connected to the incoming electric cable, manual operating means for simultaneously operating the disconnect switches of each of said switch assemblies; said manual operating means comprising a rotatable operating handle and a plurality of connected links substantially in vertical alignment having a first end pivotally connected to said operating handle; each of said disconnect switches having a rotatable actuating arm; each of said actuating arms being pivotally connected to said connected links at spaced intervals along the vertical array; said connected links having means to experience substantially linear movement under control of the rotary movement of said manual operating handle each of said switches having a rotatable side opening switch blade means; the rotational motion of said blade means lying in a plane parallel to the plane of said base member; each of said blade means being movable to an open and a closed position, wherein normal gravitational forces aids in retaining the blade means in either position to which the blade means is moved.

4. A switching arrangement for use in multiphase outdoor electrical distribution systems comprising a mounting pole; a plurality of switching assemblies equal in number to the number of phases of said multiphase system mounted upon said mounting pole; each of said switching assemblies comprising a substantially flat base member, the plane of said base member being substantially parallel to the central axis of said pole; first and second disconnect switches insulatingly mounted to said base member, said base member comprising a triangular shaped frame; first, second and third insulator members having their first ends secured to said frame at the corners thereof; fourth insulator means having its first end secured to said mounting pole at substantially the center of said frame; said first, second, third and fourth insulators being substantially parallel to one another, the second end of said fourth insulator being adapted to receive an incoming electric cable; each of said disconnect switches having a first and a second end, the first ends being secured to the second end of said first insulator; the second ends of each of said disconnect switches being secured to the second ends of said third and fourth insulators, respectively; said first end of each disconnect switch being electrically connected to the incoming electric cable, manual operating means for simultaneously operating the disconnect switches of each of said switch assemblies; said manual operating means comprising a rotatable operating handle and a plurality of connected links substantially in vertical alignment having a first end pivotally connected to said operating handle; each of said disconnect switches having a rotatable actuating arm; each of said actuating arms being pivotally connected to said connected links at

spaced intervals along the vertical array; said connected links having means to experience substantially linear movement under control of the rotary movement of said manual operating handle, said actuating arms having means to experience rotational movement under control of the linear movement of said connected links to operate said disconnect switches; each of said switches having a rotatable side opening switch blade means; the rotational motion of said blade means lying in a plane parallel to the plane of said base member; each of said blade means being movable to an open and a closed position, wherein

normal gravitational forces aids in retaining the blade means in either position to which the blade means is moved.
